UNITED STATES PATENT OFFICE.

JACOB B. BEAM, OF PUNXSUTAWNEY, PENNSYLVANIA.

RADIATOR.

1,026,896.

Specification of Letters Patent.

Patented May 21, 1912.

Original application filed February 16, 1911, Serial No. 608,944. Divided and this application filed July 26, 1911. Serial No. 640,657.

To all whom it may concern:

Be it known that I, JACOB B. BEAM, a citizen of the United States, residing in Punxsutawney, in the county of Jefferson 5 and State of Pennsylvania, have invented certain new and useful Improvements in Radiators, of which the following is a specification.

My invention relates particularly to radiators of the class employed in automobiles to cool the water which circulates in the jackets of the engine cylinders, and the object of my invention is to provide a radiator of this class which shall be strong and 15 durable, not liable to leak and which can be easily repaired when for any unusual reason any of the parts are accidentally broken.

A further object of my invention is to so construct the radiators that the radiator sections may be inserted in, or removed from 20 the rear portion of the radiator frame without detaching any part of the front frame or disfiguring the front frame with fastening devices.

25 In the accompanying drawings, Figure 1 shows a side elevation partly in section of a radiator embodying my improvements. Fig. 2 is a perspective view of one of the radiator sections employed. Fig. 3 is a detail view on an enlarged scale showing the manner of securing the radiator headers to the radiator frame. Fig. 4 is a view of two radiator headers with parts broken away to show how the securing bolts are applied.

30 The upper water chamber A is formed integrally with front and side frames M which are integral with the lower water chamber C. The front frame is formed at its upper and lower ends with flanges m , m' for the purpose hereinafter described. Pipes B and 35 D are adapted to connect the upper and lower water chambers with the water jackets of the engines. Independently removable radiator sections are employed and these are 40 of the same general construction as those shown and described in my application for Patent No. 608,944, filed February 16, 1911, of which this case is a division.

The upper water chamber A is formed at 45 its lower portion with a depressed part a which extends from the front part-way to the rear forming a shoulder a' having an opening at a'' . The lower chamber C extends only part way to the rear of the frame

and it has an opening in its rear wall c 55 surrounded by a packing c' .

The upper header E of each radiator section is formed with an upwardly projecting hollow leg E' having an opening at e which registers with the opening a'' in the upper 60 water chamber and the lower header F is correspondingly formed with a downwardly projecting hollow leg F' having an opening f which registers with the opening c in the lower water chamber. Packing x is interposed between the walls of the headers and the walls of the water chambers to make a 65 tight fit and prevent vibration.

The upper and lower radiator sections are each formed on their opposite sides with 70 semi-elliptical grooves or depressions e' and when the radiator sections are assembled there is formed an elliptical opening e'' between the headers of each two radiator sections. These openings receive securing bolts 75 G which extend through the openings e'' and engage the rear walls of the upper and lower water chambers, in the manner indicated in Fig. 3. In this way the radiator sections are secured in the radiator frame independently 80 and can be separately removed or replaced.

It will be observed that the radiator sections rest on the bottom of the radiator frame (see Fig. 1), the bottom of the radiator frame in this case consisting of the lower 85 water chamber which chamber is formed integrally with the front frame of the radiator. By thus forming the upper and lower water chambers integrally with their connecting frame a rigid structure is obtained 90 which will not so expand or contract as to affect the joints between the tubes of the radiator sections and their headers.

The construction shown and described is a simple one, the rear walls of the water 95 chambers being so formed as to receive the legs of the headers so that the latter may be readily pushed into place, bear against the shoulders of the water chambers and be held there by the short bolts which extend 100 through the recesses in the side walls of the headers, the headers not being perforated to admit such bolts.

The top walls of the headers of the radiator sections fit closely the bottom walls of 105 the upper water chamber and as the upper and lower headers are rigidly connected by the water tubes the radiator as a whole is

very rigid and strong, the upper water chamber being supported not only by the front and side frame, but also by the radiator sections which rest on the lower water chamber, as above explained. The front walls of the headers lie close to the front flanges m, m' and are concealed behind them.

I claim as my invention:

A radiator for automobiles, comprising an upper water chamber formed with a depressed portion having a rear wall provided with ports, a lower water chamber having a rear wall provided with ports, a front frame rigidly connecting the upper and lower water chambers having an inwardly projecting flange below the bottom wall of the upper water chamber and above the top wall of the lower water chamber; and a series of separately removable radiator sections, comprising lower headers which rest

on the top of the lower water chamber with their front walls close to the flange of the front frame and which have portions extending behind the lower water chamber and communicating therewith, upper headers 25 with their top walls close to the bottom wall of the upper water chamber and having their front walls arranged close to the flange of the front frame and which have upwardly projecting portions communicating with 30 the rear portion of the upper water chamber, and vertical tubes rigidly connecting the upper and lower headers.

In testimony whereof, I have hereunto subscribed my name.

JACOB B. BEAM.
